VIOLIN

Filed Dec. 12, 1923

Patented Nov. 1, 1927.

UNITED STATES PATENT OFFICE.

JOHN DOPYERA, OF TAFT, CALIFORNIA.

VIOLIN.

Application filed December 12, 1923. Serial No. 680,144.

This invention relates to and has for a main object the provision of an improved method and means for constructing violins, whereby the tone and playing qualities of the instrument will be substantially improved, and the equivalent of an expensive instrument produced or reconstructed at a nominal expense and with minor changes, with a cheap instrument employed as the basis of the reconstruction.

Another object is to provide a form of construction applicable to old or new instruments, whereby the old instruments may be so reconstructed and whereby the new instruments may be so constructed that a maximum quality of tone will be provided.

It is well known that the length of the violin influences or determines the tone, that is to say, ordinarily an instrument of a given length will have a far superior tone to an instrument of lesser length. The modern instrument, is substantially shorter than older instruments due to the fact that blocks are usually inserted at the head and tail of the instrument for reinforcing the structure, to which the neck and tail piece may be attached. These blocks extend inwardly for a substantial distance between the top and bottom and deaden the tone, likewise they serve to lessen the distance between the ends of the instrument and also to lessen the vibration area on the top and bottom.

It is an object of my invention therefore to provide an improved means whereby ample reinforcement of the structure will be provided for attaching the neck and tail piece to the body of the instrument, without shortening the effective length of the instrument, and in fact utilizing the entire length of the top and bottom and rendering the same free for vibration for improving the tone.

By the employment of the means herein-after described, it is possible to construct new violins with an increased vibration area or length and with ample rigidity, and it is further possible to reconstruct old instruments of cheap quality so as to produce

tones at least approaching in value the tones of an expensive instrument.

Other objects may appear as the description progresses.

I have shown a practical embodiment of my invention in the accompanying drawings, in which:

Fig. 1 is a top plan view of a modern violin, partly in section;

Fig. 2 is a side view of the same partly in section; and

Fig. 3 is a fragmentary sectional plan of a reconstructed violin.

Referring to the drawings, T is the top of usual form, B is the bottom and S, S are the sides which are cut into the proper shape, closely fitted and glued together. The corners between the top T, bottom B and sides S are usually reinforced by means of small beads, b, b, which may be of any suitable cross section, but are usually in the form of a segment of a circle with right angular sides abutting and adapted to be glued to the top, bottom and sides for holding these parts firmly together. Both the top and the bottom are carved out and are of convex cross section, while the sides are formed of thin veneer. As shown at one end of the instrument a neck N is firmly attached to the end, bottom and top, while at the other end the tail piece t is similarly attached. Usually the parts N and t are extended substantially inwardly from the ends and thus serve to decrease the effective length of the top and bottom.

In my improvements I terminate the said parts at the ends of the instrument, so as not to impair the tone or shorten the effective length of the instrument. This is accomplished as shown on the drawings by cutting the inner end of the neck N on a curve conforming to the sides S and affording ample stock as at 1 in the neck externally of the instrument, instead of internally as heretofore employed. The portions 2, 2 of the sides S are then turned outwardly, as shown in Fig. 1, so as to extend partially around the portion 1 of the neck and gradually

merge into said portion, so as to overlie a substantial portion of the neck so that the outer surface thereof will form a continuation of the outer surface of the neck portion

- 5 1. This is clearly shown in Fig. 1, and serves to connect the side portions 2, 2 with the neck for a sufficient distance and over a sufficient area as to hold the neck firmly in position on the instrument.
- 10 10. On the interior of the instrument, however, I provide a reinforcing strip 3 of thin material which extends over the inner end of the neck portion 1 and at its opposite ends is extended over the inner sides of the side portions 2, 2, to which it is glued and which serves to overlie the joints between the side portions 2, 2 and portion 1 of the neck. This forms an additional means of support and at the same time does not impair the quality of the instrument by any substantial reduction in the effective length. As usual in such instruments the neck N supports the finger board F which underlies the strings 5, 5 etc.
- 15 25. The opposite end of the instrument is provided with the tail part t, which is also extended outwardly instead of inwardly from the end of the instrument, and portions 6, 6 of the side S are extended around the convex surface of the part t and the sides of the instrument. The inner surface 7 of the part t is curved to conform to the curve of this end of the instrument, and a strip 8 of material overlies the joints between the portion t and the portions 6, 6 of side S in a manner similar to the other end of the instrument. Thus, the block t is held between the portions 6, 6 of the side and the strip 8 on the inside of the instrument. Also, the top T and bottom B are extended over the upper and lower sides of the block t, as shown in Fig. 2.

40 45. The tail block t serves as a means of support of the tail piece P which is connected therewith by means of the tail gut 9 attached at its ends to the tail piece P, and is looped around a peg 10 which is suitably attached to the center portion of the block t and projects outwardly from the lower end of the tail of the violin. Thus, the two opposite ends of the instrument are firmly and rigidly constructed so as to withstand the strain due to the tension of the strings 5, and although the parts are sufficiently strong and firm to withstand this strain, the effective length of the instrument is the equivalent of its actual length.

50 55. On the tail block a narrow strip of ebony as at E is suitably mounted on the upper edge so as to overlie the tail of the instrument and to receive and hold the tail gut 9 in position.

60 65. It will be further observed that by the employment of my method and means in the construction or reconstruction of an instru-

ment, the general appearance of the instrument is not changed or impaired, nor is it a departure from the standard type of instrument in vogue.

In Fig. 3 I have shown my improved method of reconstructing old violins so as to improve the tone and to conform substantially to the structure shown in connection with new violins in Figs. 1 and 2.

Referring to said Fig. 3 it will be seen that the inner end of the neck block 11 is represented by dotted lines, and that heretofore the portion 11 has extended substantially inwardly of the end of the violin, while the sides S have terminated in the sides of and against the neck block. Now, in my improvements in order to improve the tone of the instrument and to entirely remove the portion 11 from the interior of the instrument and to reinforce the neck N, I have cut the neck N at the line 13 and have extended the top board T by adding a curved extension 14 from the portion 12 where said top terminates against the neck N, and the reinforcing member 3 is inserted in the same manner as in Fig. 1 at the inner end of neck N and overlapping the joints between side extensions 15 and the sides S. Portions 15 in this case are set into the neck N so that their outer sides are flush with the edges of the neck, as clearly shown in Fig. 3.

I may modify and otherwise change my invention within the scope of the appended claims without departing from the spirit thereof.

What I claim is:

1. A violin structure comprising a body having top and bottom portions, spaced apart and formed of sheet material, side portions connecting said top and bottom, thin inner strips of material in the opposite ends overlapping the inner surfaces and adjacent ends of said sides, a neck attached to one end of the body and having a neck block overlapping and abutting the adjacent inner strip of material at one end of said body, and extended outwardly therefrom, the extremities of the sides overlying said block outwardly of the body and merging therewith, a tail block at the opposite end of the body abutting said inner strip of material and extended outwardly therefrom, the adjacent ends of said sides being curved around and attached to the outer surface of said tail block, said top and said bottom being extended outwardly over said neck and tail pieces, for the purpose described.

2. A violin comprising a body having a top and a bottom, sides connecting said top and bottom and formed of thin strips of material with the adjacent ends thereof spaced apart at one end, thin strips of material in the ends overlapping and internally of the adjacent portions of said sides, a tail block at one end thereof abutting one of

said inner strips of material and curved outwardly therefrom, the adjacent end portion of said sides being curved outwardly around said tail block for reinforcing one end of said body, a neck attached to the other end of said body, including a block abutting said inner strip of material at said other end, said neck block being extended outwardly and

recessed in the sides to receive, and said sides being held in said recessed portions and extended outwardly over the sides of said neck block, for securing said neck in position for use, and said top and bottom members being extended at the ends over both of said blocks, as described. ¹⁰
